UNITED STATES PATENT OFFICE

HENRY C. MAUL, OF DETROIT, MICHIGAN, ASSIGNOR TO DETROIT-MICHIGAN STOVE COMPANY, OF DETROIT, MICHIGAN, A CORPORATION OF MICHIGAN

GAS STOVE

Application filed August 19, 1929. Serial No. 386,750.

The present invention pertains to a novel gas stove of the more recent type wherein the valves are obstructed from view by a front wall or plate and wherein the valves are operated by handles at the outer face of the plate, these handles cooperating with index points on the plates to give the appearance of an electric range.

Due to this construction, the front range of the burners is often in close proximity to the air inlets of the mixing pipes leading thereto. Consequently there is an increased danger of back firing or preignition, particularly when the burner is covered by a large pot, or in the case of closed top stoves or in the use of natural gas.

The principal object of the present invention is to overcome this difficulty and is accomplished essentially by the insertion of a baffle between the burner and the air inlet to the mixing chamber, whereby the flame issuing from the burner is positively prevented from reaching the air inlet. The baffle plate is secured in a convenient and suitable manner to the front plate which also is spaced from the top plate to permit access of air to the air inlet of the mixing tube.

The invention is fully disclosed by way of example in the following description and in the accompanying drawings in which

Fig. 1 is a plan view, partly in section, of a stove constructed according to the invention, and

Fig. 2 is a longitudinal vertical section thereof.

Reference to these views will now be made by use of like characters which are employed to designate corresponding parts throughout.

The stove is shown as comprising a body supported on legs 2 in the usual manner. The body has a front wall 4 extending upwardly nearly as far as the top plate or frame 5 which is supported on the upper edge of the lateral and rear walls of the body, as shown more clearly in Fig. 2.

The inlet manifold 6 is supported near the upper edge of the wall member 4, at the inner face thereof, by means of brackets 7 formed on or attached to the inner face of the front wall. These brackets have curved seats

8 in which the pipe 6 rests, and the latter is secured in place by means of straps 9 secured to the inner end of the brackets by means of bolts 10.

A front set of burners 11 is supported on a rod 12 at the usual distance from the front of the stove. The manifold 6 has connected thereto a corresponding number of gas cocks 13 at suitable intervals. Nozzles 14 are coupled to the gas cocks, as at 15, and project into the mixing tubes 16 of the respective burners, which tubes are formed with air admitting bell mouths 17 in the usual manner. The mixing tubes of the front burners 11 must be of a definite length to perform their intended function, and in order to provide such length in the construction illustrated, where the manifold is behind the front wall of the body and the front burner is spaced no farther than usual from the front wall, the tubes are connected to rearward points of the burners, as indicated by the numeral 18.

Rear burners 19 are also provided, and supported on a transverse rod 20, but owing to the distance of these burners from the front wall 4, a proper length of mixing tube is provided regardless of the point of attachment to the burners.

A grating 22 exposing the burners and adapted to support cooking utensils over the burners is mounted in the top plate 5 in the usual manner. The tubes 21 are formed with air admitting bell mouths 23 similar to the members 17 and in line therewith, as shown more clearly in Fig. 1. The manifold 6 carries additional gas cocks with nozzles projecting into the members 23, but, inasmuch as these are identical to those already described, further detailed description is not deemed necessary.

The gas cocks have stems 24 passing through the front wall 4 and equipped on the outer side of the wall with integral operating knobs 25 and pointers 26. For each pointer, there is formed on the wall 4 a series of co-operating index points for showing various adjustments of the corresponding gas cock, as fully disclosed in my copending application Serial No. 321,787, filed Nov. 26, 1928.

The positioning of the gas cocks at the inner side of the front wall has the effect of bringing the bell mouths 17 close to the front burners 11 due to the fact that the latter are 5 not spaced from the front edge of the plate 5 any farther than in the previous constructions.

Due to the close proximity of the air admitting mouths to the front burners, there is 10 an increased danger of back-firing or pre-ignition under various circumstances, such as in the use of natural gas, in the use of a closed top over the burner, or by the spreading of the flame when a large vessel is placed over 15 the burner. To overcome this difficulty, there is provided a baffle 27 having a doubled or stiffened lower edge 28 resting upon the tubes 16 behind the mouths 17 thereof and lying between the mouths and the forward burners 20 11 communicating with the corresponding tubes 16. The upper edge of the baffle plate is bent at an angle, as at 29, to lie against the upper ends of the straps 9 in order to be secured thereto by the upper bolts 10.

25 The baffle plate further has an upper angular rib 30 engaging the top plate 5 to prevent the burner flame from passing around the manifold pipe to the air admitting mouth 17. It will be apparent that the mouths 17 30 are thus fully shielded from the flames of the forward burners 11, while air from the atmosphere has access to these mouths through the space 31 between the front wall 4 and the plate 5.

35 Although a specific embodiment of the invention has been illustrated and described, it will be understood that various alterations in the details of construction may be made 40 without departing from the scope of the invention and indicated by the appended claims.

What I claim is:—

1. In a gas stove, a front wall having brackets extending inwardly therefrom, a 45 manifold clamped to said brackets, a gas cock depending from said manifold, a burner at the inner side of said wall, a mixing tube communicating with said burner and having an air inlet in close proximity thereto, a nozzle 50 projecting from said gas cock into said inlet, and a baffle inserted between said burner and inlet and secured to said brackets.

2. In a gas stove, a front wall having brackets extending inwardly therefrom, a 55 manifold clamped to said brackets, a gas cock depending from said manifold, a burner at the inner side of said wall, a mixing tube communicating with said burner and having an air inlet in close proximity thereto, a nozzle 60 projecting from said gas cock into said inlet, a baffle inserted between said burner and inlet and secured to said brackets, and an operating handle for said gas cock disposed at the forward side of said wall.

65 3. In a gas stove, a front wall having

brackets extending inwardly therefrom, a manifold clamped to said brackets, a gas cock depending from said manifold, a burner at the inner side of said wall, a mixing tube communicating with said burner and having an air inlet in close proximity thereto, a nozzle 70 projecting from said gas cock into said inlet, and a baffle inserted between said burner and inlet and secured to said brackets, and a top plate spaced above said front wall 75 to permit access of air to said air inlet.

In testimony whereof I affix my signature.
HENRY C. MAUL.
